UNITED STATES PATENT OFFICE.

LORENTZ E. EGAR AND NIELS C. L. WILHEJLM, OF BROOKLYN, NEW YORK, ASSIGNEES
TO AUTOMATIC TEMPERATURE CONTROL CO., A CORPORATION OF NEW YORK.

AUTOMATIC VALVE-REGULATOR.

1,397,680.

Specification of Letters Patent. Patented Nov. 22, 1921

Application filed November 29, 1919. Serial No. 341,365.

To all whom it may concern:

Be it known that we, LORENTZ E. EGAR, citizen of the Norwegian Monarchy, and NIELS C. L. WILHJELM, citizen of the Danish Monarchy, residing both in Brooklyn, Kings county, New York, have invented certain new and useful Improvements in Automatic Valve-Regulators, of which the following is a specification.

10 This invention relates to automatic valve regulators. More particularly the invention relates to improvements in electrically operated valve regulating mechanisms of the type used in combination with a pyrometer or similar apparatus for regulating fuel supply controlling valves in the supply pipes to furnaces.

One object of the invention is to provide an electrically operated valve control apparatus adapted to be manufactured in unit form to be connected to the supply control valves and adapted to operate said valve automatically and in practically immediate response to changes in the temperature in the furnace and in combination with a temperature registering device such for instance as a pyrometer.

Another object of the invention is to provide a control apparatus containing an improved form of make and break device of simple and practical construction and design.

Still another object is to provide an apparatus adapted to be efficiently operated by a small electric motor.

Other objects of the invention and the manner in which the invention operates and the advantages to be derived therefrom will appear hereinafter.

Accordingly our invention comprises all parts, elements, arrangements and combinations thereof as are hereinafter set forth while reference is had to the accompanying drawings in which—

45 Figure 1 is a diagrammatic view illustrating the use and operation of our invention together with the wiring diagram in which it is connected.

50 Fig. 2 is a side view of a snap switch or make and break device used in our valve regulator, with parts in section and parts broken away.

Fig. 3 is a plan view of said snap switch.
Fig. 4 is an elevation of our unit form
55 valve regulator.

Referring first to Fig. 1 the reference numeral 6 denotes a furnace of any suitable construction having a fuel supply pipe 7 in which 8 indicates a suitable supply controlling valve provided with an operating element or handle 9. 10 indicates diagrammatically a millivolt-meter or like temperature indicating device in which an armature or element 11 is movable between two contacts 12 and 13 in response to temperature changes in the furnace. The moving element 11 is operated by a thermocouple 14 or like temperature measuring device to which it is connected by wires 15 and 16. As shown in Fig. 1 the reference numeral 14 indicates, partly in section, a pyrometer of the Le Chatelier type by way of illustration. 60 65 70

Our improved valve regulator comprises a snap switch 18 adapted to make contact at 19 or 20 when operated by a slide 21 which is pivoted at 22 to a link 23. This link is in turn pivoted at 24 to a crank disk 25 operated through suitable reducing gearing 26 from a motor 27. 28 is a valve operating lever which is pivoted to the link 23 at 29 and which lever swings about a relatively fixed pivot 30. The lever is connected to the valve handle 9 by a link 31. 75 80

The use and operation of pyrometers and thermocouples are well known in the art and need no description here. For the purpose of understanding our invention the following explanation of the diagram shown in Fig. 1 will be sufficient. 90

So long as the temperature in the furnace 6 remains at the desired or required degree, the pyrometer merely registers said temperature. If now the temperature increases the element 11 which is responsive to temperature changes moves to the left, for instance, and makes contact at 12. The electric current then passes from the line wire 33, through 11 and 12, wire 34, 19 and 18 through wire 35 to the motor 27 and out 100 through the line 36. The motor commences to operate and rotate crank disk 25 through gearing 26. Consequently link 23 is moved upward and through lever 28 and link 31 the valve is closed thus decreasing the fuel supply to the furnace. But simultaneously therewith the slide 21 has also been operated to snap the switch 18 from contact 19 to contact 20 whereby the circuit through the motor is broken and the operation of the 110

valve stopped, the fuel supply will be diminished and the temperature in the furnace will be decreased.

If on the other hand the furnace temperature decreases, the element 11 will move to contact with 13. The current will then pass from the line 33, through 11, 13, wire 38, contact 20, switch 18 through the motor and out. The motor will again operate the lever 10 23, lever 28 and link 31, but in the reverse direction to open the valve 8 and at the same time slide 21 will be actuated to operate the switch 18 to break the motor circuit. So that in this event the valve 8 will open to 15 permit of an increased fuel supply to the furnace.

Referring now to Figs. 2 and 3 for a detailed description of the switch it will be seen that it is generally contained within a 20 casing 40 in which the switch 18 is pivoted at 41 in a bearing 42. The contacts 19 and 20 are suitably located and adapted for their respective wire connections which may pass through terminals 43, 43. The switch 18 has 25 a nonconducting blade 44 which carries conducting contacts 45, 46 connected by a conductor 47 which latter is connected by wire 48 to binding post 49 from which a flexible connection 50 leads to binding post 51 for 30 wire 35, see Fig. 1. The other end of blade 18 is formed with a loop 52 terminating in a tongue 53. 54 is a spring pressed abutment slidably mounted in a guide 55 which is slotted as at 56 to provide play for the pin 35 57. The abutment under tension by the spring 58 prevents lateral movement of the switch as shown in that the abutment projects into the path of the tongue 53. The numerals 59 and 60 denote locking members 40 or cams pivoted on the bearing 42 at 61, 61. The aforesaid slide 21 carrying the pivot 22 slides underneath the switch in a guide 62 and carries a pin 63 connected to the switch blade 18 by means of a laminated spring 64. 45 The position of the parts as illustrated in Fig. 3 show clearly that the switch is firmly locked by the abutment 54 which prevents lateral movement of blade 18. When, however, as explained above, the slide 21 is operated, its pin 63 will be moved toward the cam 59 and the spring 64 will be flexed tending to snap the blade 18 from contact 19 to contact 20. The movement of the pin 63 continues until it abuts cam 59 and moves the 50 latter around its pivot 61, the result of which movement will be that the cam in swinging presses back, to the left in the drawing, the pin 57 and the abutment 58. As soon as the latter has moved out of the 55 path of the switch tongue 53, the blade 18 on the pressure of the flexed spring 64 will snap quickly to contact 20 breaking the contact at 19 after which the parts will assume the same positions as in Fig. 3 except that 60 65 the switch will now be locked in the oppo-

site position with the tongue 53 on the other side of the abutment 54. When the slide 21 is again operated, which will be in the reverse direction, the reverse movement takes place in the switch during which the slide 70 pin 63 acts on the cam 60 to operate the abutment 54 as will be understood.

It is one of the features of this invention to provide an automatic valve regulator in unit form, that is to say such a form that 75 the regulator as such may be manufactured and assembled ready to be connected in the circuit and to the valve. Fig. 4 illustrates one embodiment of this feature of the invention in which the numeral 70 denotes a 80 suitable base upon which is mounted the motor 27. The gearing 26 for operating the crank disk 25 comprises a worm 71 on the motor shaft 72, a double pinion 73—74 which transmits the motion of the shaft to 85 the crank disk gear 73. In order to allow for the necessary adjustments the pivot 30 is carried by a block 74 which is slidably mounted in a guide 75 and operated by an endless screw 76. The pivot 30 moves in the 90 slot 77 in the lever 28 which is also provided with apertures 78 to adjust the active length of the arm 28 from the pivot 29 as will be understood. The stroke adjusting screw 76 is placed in an inclined position to 95 the lever 28 to prevent closing the valve below a predetermined minimum if only part of the flow is controlled. If the valve is entirely closed it cannot be forced down too much. The switch is placed on the base 70 100 as shown and the entire device is compact and easily operated and installed.

The invention as herein described and illustrated may be used for the control of valves, gates, dampers and the like in connection with any measuring instrument constructed so that an electric circuit is closed when the indication of the instrument exceeds the given point on its scale, and another circuit is closed when the indication falls below the given point. No current is carried through any parts of the apparatus when not operating thus decreasing the wear thereof. It will further be noted that the current is not broken in the controlling or 105 measuring instrument so that no destructive sparking takes place therein. The motor affords a convenient operating means using but very little current. The motor is geared down so that the operation of the valve 110 takes place slowly and no sudden strains are experienced in the device.

It will further be understood that we do not intend to be limited by anything stated in the foregoing but that changes may be 115 made in the apparatus and invention within the scope of the appended claims.

We claim:—

1. In combination, a furnace, a valve, for controlling the fuel supply thereto, an elec- 120

125

130

- tric circuit including a device responsive to temperature changes in said furnace, a regulating mechanism comprising a motor and means actuated by said motor for operating 5 the said valve, electrical connections in said circuit between the said device and the said motor for starting the latter to operate said valve when the temperature in the furnace varies from a predetermined constant and a 10 switch operated by said motor to break the said connections between the latter and the said device after the said valve has been operated and means carried by said switch for locking it when the circuit is closed.
- 15 2. In combination, a furnace, a valve for controlling the fuel supply thereto, an electric circuit including a device responsive to temperature changes in said furnace, a regulating mechanism comprising a motor 20 for operating the said valve, electrical connections in said circuit between the said device and the said motor for starting the latter to operate the said valve when the temperature in the furnace varies from a 25 predetermined constant, a switch, means for operating said switch from the said motor after the said valve has been operated and means in said switch for automatically breaking the connections between the said device and the said motor subsequent to the 30 said operation of the said valve and means carried by said switch for locking it when the circuit is closed.
3. In combination, a furnace, a valve for controlling the fuel supply thereto, an electric circuit including a device responsive to temperature changes in said furnace, an element for operating the said valve, means for adjusting the extent of operation of said element and additional means for adjusting 35 the throw of said valve, a motor for actuating said element, connections in said circuit between the said device and the motor for starting the latter when the temperature in the furnace varies from a predetermined 40 constant, a switch for controlling the direction of current in said connections and means actuated by said motor for operating said switch to automatically break the said connections between the said device and the 45 motor after the latter has operated the valve.

Signed at New York, N. Y., November 22nd, 1919.
